[57] CLAIM

The ornamental design for a pipe restrainer collar member, as shown.

DESCRIPTION

FIG. 1 is a perspective view of a pipe restrainer collar member showing our new design;
FIG. 2 is a rear elevational view thereof;
FIG. 3 is a front elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a perspective view of a second embodiment of the design shown in FIG. 1;
FIG. 9 is a rear elevational view thereof;
FIG. 10 is a front elevational view thereof;
FIG. 11 is a right side elevational view thereof;
FIG. 12 is a left side elevational view thereof;
FIG. 13 is a top plan view thereof;
FIG. 14 is a bottom plan view thereof;
FIG. 15 is a perspective view of a third embodiment of the design shown in FIG. 1;
FIG. 16 is a rear elevational view thereof;
FIG. 17 is a front elevational view thereof;
FIG. 18 is a right side elevational view thereof;
FIG. 19 is a left side elevational view thereof;
FIG. 20 is a top plan view thereof;
FIG. 21 is a bottom plan view thereof;
FIG. 22 is a rear elevational view thereof;
FIG. 23 is a front elevational view thereof;
FIG. 24 is a right side elevational view thereof;
FIG. 25 is a left side elevational view thereof;
FIG. 26 is a top plan view thereof; and,
FIG. 27 is a bottom plan view thereof.
